Primary Examiner—Holly H. Baynham

(21) Appl. No.: **29/196,398**

(57) **CLAIM**

(22) Filed: **Dec. 30, 2003**

The ornamental design for the railing bracket radiussed, as shown.

(51) **LOC (8) Cl.** 08-05

DESCRIPTION

(52) **U.S. Cl.** D8/354

FIG. 1 is a perspective illustration of a railing bracket radiussed illustrating the said ornamental design

(58) **Field of Classification Search** D6/354;

FIG. 2 is a front elevation of the railing bracket radiussed of FIG. 1;

D8/349, 356, 366, 373, 380, 394, 363, 364;

FIG. 3 is a rear elevation of the railing bracket radiussed of FIG. 1;

D25/199; 256/59, 66, 65.05; 248/27.1;

FIG. 4 is a left side elevation of the railing bracket radiussed of FIG. 1;

403/171, 187, 192, 230, 260, 262

FIG. 5 is a right side elevation of the railing bracket radiussed of FIG. 1;

See application file for complete search history.

FIG. 6 is a top plan view of the railing bracket radiussed of FIG. 1; and,

(56) **References Cited**

FIG. 7 is a bottom plan view of the railing bracket radiussed of FIG. 1.
